UNITED STATES PATENT OFFICE.

WILLIS E. AUSTIN, OF MINNEAPOLIS, MINNESOTA.

PNEUMATIC ACTION FOR MUSICAL INSTRUMENTS.

1,295,672.

Specification of Letters Patent. Patented Feb. 25, 1919.

Application filed July 20, 1916. Serial No. 110,307.

To all whom it may concern:

Be it known that I, WILLIS E. AUSTIN, a citizen of the United States, resident of Minneapolis, county of Hennepin, State of Minnesota, have invented certain new and useful Improvements in Pneumatic Actions for Musical Instruments, of which the following is a specification.

My invention relates to a pneumatic action for organs and other wind instruments and the object of the invention is to provide a pneumatically operated motor for controlling the mechanism of the instrument which will be positive and reliable in its action, 10 easily accessible, and removable for substitution or repairs, and which will dispense entirely with the ordinary bellows pneumatic and pouch action or control incidental to a pneumatically operated musical instrument.

A further object is to provide a motor and valves operated thereby which can be utilized in different parts of the instrument for controlling the flow of the air pressure.

Other objects of the invention will appear from the following detailed description.

The invention consists generally in various constructions and combinations, all as hereinafter described and particularly 30 pointed out in the claims.

In the accompanying drawings forming part of this specification,

Figure 1 is a sectional view of the wind chest of a pipe organ, illustrating the application of my improved motor for operating a single valve,

Fig. 2 is a sectional view on the line $x-x$ of Fig. 3, looking down on the motor frame,

Fig. 3 is a view illustrating the motor frame,

Fig. 4 is a sectional view looking up from the section line $x-x$ of Fig. 3,

Fig. 5 is an edge view of the motor frame,

Figs. 6 and 7 are detail views of the oscillating valve support or plate showing the valve and pouch member.

Fig. 8 is a sectional view of a device for operating a double arrangement of valves, showing the motor with reciprocating member mounted in the wind chamber.

Fig. 9 is a plan view, taken on the line $y-y$ of Fig. 8, showing part H removed.

In the drawing, Fig. 1, A and A' represent the motor frame, B and B' movable plates or supports, and C pouch members thereon. These pouch members are of flexi-

ble material mounted on the inner faces of said plates and project outwardly beyond the edges thereof. D represents sheets of flexible packing interposed between the frames A and A' and the motor bar E. L represents an air pressure chamber surrounding the frames or motors, as they may be termed, and normally containing air under pressure. N and N' represent valves mounted respectively on the supports B and B' and O is a passage leading from the valves to the pipes (not shown) of the organ. T represents the top board of the wind chest, U and U' the side boards thereof, and V the bottom board. This board incloses the pressure compartment L and the motors and valves. Normally the passage K will be under pressure, the air being supplied as in common practice under control of a valve (not shown) and when it is released, as by the movement of a key of the organ, the pressure in the chamber L being in excess of the reduced pressure in K will unseat the valve M and admit air to the passage O and the pipe. When sufficient pressure is allowed to enter the passage K, the position of the plate will be reversed and it will move outwardly to again seat the valve N and cut off the flow of air from the chamber to the pipe. The frame A has an opening B'' into which the support B is inserted, and said frame has a chamfered surface A'' (see Fig. 3) upon which the flexible edges of the pouch member C are adapted to rest, said edges fitting between the frame A and the packing D, one end of said pouch member forming a hinge on which the support B may rock back and forth within the opening B'' to seat or unseat the valve M. The packing D, as indicated in Fig. 5, is secured to the surface of the frame A at the top and sides but at the bottom is left loose or detached so that it can be bent outwardly to permit the insertion of the support B into the opening B''. To allow the support B to rock in its supporting frame, I provide thereon a beveled lower edge C'' which allows sufficient movement of the support to open or close the valve. The pouch member C of this support bearing on the edge of the opening in the frame, has the function substantially of a packing for the oscillating support to prevent the escape of air. The space at the rear of the flexible member C and with which communicates the passage K constitutes in effect a chamber receiving

air from passage K and permitting the valve to move toward the same when air pressure therein is reduced and the excess of air pressure in wind chest chamber L moves the valve in that direction in unseating the valve. When the support B is moved to seat the valve N and close the passage Q, the edges of the pouch member will be held by the pressure in the passage K against the 10 chamfered edge of the opening B' and there will be no escape of air around this edge while, whenever desired, the support B and the valve can be readily removed from the frame through the opening therein without 15 the necessity of detaching any other part of the pneumatic action. Obviously this is a decided advantage in a device of this kind, as it permits the quick and convenient renewal of a valve or of the pouch member 20 carried by the valve support without the necessity of taking the apparatus in pieces. I regard this movable feature of the valve supporting means as an important part of my invention.

25 In Fig. 8 I have shown a motor device for operating a double arrangement of valves. The principle is practically the same as the one described, except that the valve support moves in a straight line and the valve is not 30 directly mounted on the support, thereby adapting the movement for another function in the instrument. In this view, G represents a constant pressure compartment or the space containing air under pressure. H is the upper half of the motor chamber and H' is the lower portion thereof. I is the 35 port controlled by the valves M and M'. P is a movable member. Q and Q' are the chamfered surfaces of the motor chamber 40 and R is the pouch member mounted to rest on the said surfaces and S is a rod connecting said moving member with the valves M and M'. J is a port communicating with the motor chamber. When the pressure is 45 released on one side of the motor the valves will be operated to open or close the port I leading to the chamber G, at the same time closing and opening the vent to the outer atmosphere in a similar manner, as shown 50 and described with reference to the construction in Fig. 1.

The valves and motors shown in the several figures are adapted for use in different parts of a pipe organ and may also be employed for a variety of uses in the action of other musical instruments controlled or actuated by air pressure. I do not wish, therefore, to be confined to the specific illustration and use of the invention herein described.

60 I claim as my invention:

1. In a pneumatic action, a frame having an opening therethrough, a support for said frame, a valve supporting means and valve seated to rock on said frame and mounted to 65 move within said opening in actuation of the

valve, said valve supporting means being insertible into and removable from said frame.

2. In a pneumatic action, a frame and valve and a support for the valve, a flexible member attached to said support and bearing freely against the frame, said valve and support being separable from the frame, an opening being formed at the lower end of the frame through which said valve and support may be inserted and removed.

3. In a pneumatic action, a motor comprising a frame having an opening therein, a valve supporting means having a pouch member extending beyond the edges thereof, 80 said frame having a surface whereon said pouch member is adapted to rest, said valve-supporting means being mounted to rock at one end on said frame within said opening to seat or unseat said valve.

4. In a pneumatic action, a frame having an opening therein provided with a chamfered edge, a valve-supporting means having a pouch member to rest on said chamfered edge, said pouch member at one end of 90 said means being seated in said frame and forming a hinge on which said valve-supporting means rocks in said opening, and a valve carried by said means.

5. In a pneumatic action, a frame having 95 an opening therein and a packing encircling said opening, a valve support having a flexible member thereon fitting between the edge of said opening and said packing and resting on the edge of said opening, said support having a movement within said opening, the support and its flexible member being removable, a valve carried by said support and means for creating unequal pressure upon opposite sides of said support. 100

6. In a pneumatic action, a frame having an opening therethrough, a valve-supporting member fitting within and closing said opening and mounted to rock at one end in said frame, and a valve carried by the opposite end of said member.

7. In a pneumatic action a motor frame, and a packing therefor, said frame and packing having openings therein, a support fitting within said opening and having a pouch member to lap by the edge of said opening between it and said packing, said support rocking on one end of said frame and a valve carried by said support and opened and closed by the rocking thereof.

8. In a pneumatic action a motor frame having an opening therein, a support fitting within said opening and having means bearing against the frame around said opening for preventing the escape of air between it and said frame, said support being mounted to rock on said frame in said opening, a valve carried by said support and means for creating unequal air pressure on opposite sides of said support.

9. In a pneumatic action, a frame having an opening therein, a support for said frame, a packing interposed between said frame and support, a gap being provided 5 between the edge of said opening and said packing, a plate having a pouch member on one side projecting beyond the edges thereof and fitting into said gap, said plate fitting loosely within said opening and said pouch 10 member resting on the edge thereof, and a valve carried by said plate.
10. In a pneumatic action, a movable member mounted in a chamber and provided with a flexible member disposed to bear 15 against the wall of said chamber, said flexible member being free and unattached except to the movable member, a valve connected with the movable member, and means for creating unequal pressure upon opposite 20 sides of the movable member.
11. In a pneumatic action musical instrument, a movable member mounted in a chamber and provided with a flexible member disposed to bear against the wall of said 25 chamber, said flexible member being free and unattached except to the movable member, a sound-producing control member actuated by the movable member, and means for creating unequal pressure upon opposite 30 sides of the movable member.
12. In a pneumatic action musical instrument, a base structure having a pipe opening and a valve closing air pressure chamber, a freely movable member and a valve 35 associated therewith to control the pipe opening, said member and valve being positioned intermediate of said air chamber and pipe opening, and movable into valve closing position by air pressure in the air chamber, and a projecting flexible strip carried 40 by said movable member to prevent passage of air from one side to the other thereof and free and unattached except to said member.
13. In a pneumatic action musical instrument, a base structure having a pipe opening and a valve closing air pressure chamber, a freely movable member and a valve 45 associated therewith to control the pipe opening, said member and valve being positioned intermediate of said air chamber and pipe opening and movable into valve opening and closing position by air pressure acting on said movable member, and a project- 50
- ing flexible strip carried by said movable member to prevent passage of air from one side to the other thereof and free and unattached except to said member. 55
14. In a pneumatic action musical instrument, a base structure having an air conduit and a valve closing air pressure chamber, a freely movable member and a valve associated therewith to control the air conduit, said valve being positioned intermediate of said air chamber and air conduit and movable by air pressure on said member into 60 position to control the air conduit, and a projecting flexible strip carried by said movable member to prevent passage of air from one side to the other thereof and free and unattached except to said member. 65
15. In a pneumatic action musical instrument, a base structure having a valve closing air pressure conduit and air chamber, a freely movable member and a valve associated therewith to control the air conduit, 70 said valve being positioned intermediate of said air chamber and air conduit and movable by air pressure on said member into position to control the air conduit, an apertured member in which said movable member is free to move and formed with a chamfer, and a projecting flexible strip carried by said movable member and positioned to bear against the chamfer of the apertured member, said strip being free and unattached 75 except to said movable member. 80
16. In a pneumatic action musical instrument, a base structure having a valve closing air pressure conduit and air chamber, a freely movable member and a valve associated therewith to control the air conduit, 85 said valve being positioned intermediate of said air chamber and air conduit and movable by air pressure on said member into position to control the air conduit, an apertured member in which said movable member is free to move, a projecting flexible strip carried by said movable member and free and unattached except to said member, 90 and a seat of flexible material associated 95 with the apertured member and on which the flexible strip freely seats. 100

In witness whereof I have hereunto set my hand this 17th day of July, 1916.

WILLIS E. AUSTIN.
